THOMAS B. BASH, OF KANSAS CITY, MISSOURI, ASSIGNOR TO JAMES R. KEARNEY CORPORATION, OF ST. LOUIS, MISSOURI, A CORPORATION OF MISSOURI

DRIVING MEANS FOR GUY ANCHORS

Application filed July 27, 1928. Serial No. 295,793.

This invention relates to driving means for guy anchors and particularly to a wrench for driving or setting an anchor of the screw type, such as are ordinarily used in connection with overhead electric lines and the like.

Ground anchors for the purpose mentioned, are usually set in the ground at an angle to the vertical, and this practice involves a difficulty when the anchor is nearing its final position, in that the turning of the driving wrench is interfered with by the surface of the earth. An object of my invention is to obviate this difficulty, and to provide a driving tool or wrench which will enable the driving or setting of an anchor with greater ease, and in less time, than has heretofore been accomplished.

A further object is to provide an improved instrument or tool which conforms to, and is adapted for use with certain anchors of the prevailing types.

Other objects and advantages will appear from the following detailed description of parts and the accompanying drawings, in which Fig. 1 is a partial, sectional elevation, showing an anchor of the auger type, with which a preferred embodiment of this invention is illustrated; Fig. 2 is a section along the line 2—2 in Fig. 1; Fig. 3 is a section along the line 3—3 of Fig. 1 and includes a plan of the wrench body, suitably positioned for turning the wrench.

Referring by numerals to the drawings, the screw anchor 4, of prevailing form, has a recess 5 adapted to receive and serve as a seat for one end of a wrench tube 6. The recess in the anchor, is polygonal in cross section, and preferably square, as shown. The recess 5 and the wrench tube 6 are so proportioned that the wrench member may be readily inserted into the recess, but cannot turn, without imparting its movement to the anchor body. Centrally located in the anchor body, preferably just below and opening into the recess 5, is a tapped opening 7, to receive a threaded portion of the anchor rod 8, which is adapted to extend through the wrench tube. The upper end 50 of the anchor rod is threaded to receive an

anchor eye 9. The anchor eye is preferably provided with a shoulder 10 which is adapted to serve as an abutment for the outer end of the wrench tube, and insure its remaining in the recess 5, while the anchor is being driven.

The essential feature of the present invention is a wrench body 12, provided with an opening such as the hole 13, polygonal in outline and of a shape and size to allow free longitudinal movement therethrough of the wrench tube, but which prevents the turning of the wrench body without corresponding motion of the tubular member. The wrench body may be moved to a height on the wrench tube, suitable to the operator, where it is held in detachable engagement with the tube by means of a set screw 14, or the equivalent. At each end of the wrench body, and preferably perpendicular to its longitudinal axis, are the apertures 15, which receive the handles 16, and are of a size to permit free movement of the handles therein. Cotter keys 17 or their equivalents, are provided at the ends of the handles and prevent the casual or accidental removal of the handles from their apertures.

The assembly and use of the wrench will be apparent from the preceding description of its parts, but may briefly be described as follows: After the anchor rod 8 has been screwed into the tapped opening 7 in the anchor body, the wrench tube, with the wrench body attached, is positioned over the anchor rod and one end seated in the recess 5. The eye 9 is then threaded onto the opposite end of the anchor rod, and the anchor is ready to be driven into the ground by turning the handles 16 about the axis of the anchor body. It may be noted that in setting the anchor, the torque incident to turning the wrench, is transmitted to the anchor, solely through the tube; the purpose of the present use of the anchor rod in the particular example shown, being to preclude the casual slipping of the tubular member out of the recess or seat in the anchor body, and to occupy the tapped hole 7, so that it will not be filled with earth during the setting or driving operation.

If the particular installation, as usual, requires that the anchor be driven out of plumb with the horizontal, the handles may be used in their outermost positions until the earth surface interferes with their turning. The obstructed handle is then moved across the wrench body sufficiently to clear the earth's surface.

When the anchor reaches its final position, the anchor eye is unscrewed, the tube and wrench body removed, and the eye replaced, after which the anchor may be put into service.

By my provision of a wrench which is socketed to receive the wrench tube, and equipped with the movable handles described, I am enabled to dispense with the use of the ordinary wrenches, which are not suited for this class of work, and I eliminate, entirely, the labor, delay and inconvenience which are incident to the removal of the wrench, each time the tube has completed only a part of a revolution.

It will be understood that the described example constitutes only a single, practical embodiment of the present invention, and that obvious changes may be made; for instance, in the sectional shape of the tubular member; in the shape of the wrench body and handles, in the manner of securing together the component parts of the assembly, and in other details of construction, without departing from the scope of the invention as defined by the appended claim.

I claim as my invention:

In a wrench for driving a screw type ground anchor having an anchor rod and an eye, a wrench assembly comprising a wrench tube of polygonal section adapted to be inserted in the anchor in driving relation therewith, a wrench body having a polygonal opening therethrough for reception of the wrench tube, said body being adjustable along said tube and held in adjusted position by a set screw, said body having a pair of parallel circular openings therethrough transverse to the said tube opening and arranged one on each of the opposite sides thereof and parallel to opposite faces of the polygon and closely adjacent thereto, a slidably handle in each of said circular openings and handle retaining means located at the ends of said handles.
